RAILWAY SWITCH OPERATING APPARATUS

Herbert L. Bone, Forest Hills, Pa., assignor to
The Union Switch & Signal Company, Swiss-
vale, Pa., a corporation of Pennsylvania

Application November 27, 1937, Serial No. 176,836

19 Claims. (Cl. 246—291)

My invention relates to railway switch operating apparatus, and particularly to apparatus for operating spring switches.

More particularly, my present invention relates to apparatus of the type in which there is mounted in a single housing manually operable means for moving the switch between its two extreme positions, means for biasing the switch to whichever extreme position it is moved by said manually operable means, means for locking the switch in one of its extreme positions in such manner that it will become automatically unlocked when a train trails the switch, and means effective when a train trails the switch to force the movable rails of the switch to, and hold them in, positions opposite to their initially set positions until after the train has completely passed the switch, whereupon the movable rails are permitted to return to their initially set positions.

One object of my invention is the provision in apparatus of the type described of pneumatic means actuated by the movement of the switch when a train trails the switch for forcing the movable rails to their trailed positions and holding them there until after the trailing train has passed the switch.

Other objects and characteristic features of my invention will appear as the description proceeds.

I shall describe two forms of apparatus embodying my invention, and shall then point out the novel features thereof in claims.

In the accompanying drawings, Fig. 1 is a top plan view showing a railway switch A provided with one form of switch operating mechanism embodying my invention. Fig. 2 is an enlarged view, partly in section and partly in elevation of the operating mechanism shown in Fig. 1. Fig. 3 is a top plan view of the mechanism shown in Fig. 2, certain of the parts being removed and others being shown in section, to better illustrate the construction of the remaining parts. Fig. 4 is a diagram illustrating by characteristic curves the operating characteristics of the mechanism shown in the preceding views. Fig. 5 is a sectional view of the spring unit 35 forming part of the mechanism shown in Figs. 2 and 3. Fig. 6 is a view similar to Fig. 3 showing a modified form of apparatus embodying my invention. Fig. 7 is a sectional view of a portion of the apparatus shown in Fig. 6. Fig. 8 is a diagram showing by characteristic curves the operating characteristics of the mechanism shown in Fig. 6.

Similar reference characters refer to similar parts in each of the several views.

Referring first to Fig. 1, the reference character A designates a railway switch comprising, as usual, two fixed rails 1 and 1a and two movable rails 2 and 2a. The fixed rails 1 and 1a are laid on tie plates 3 and are secured to crossties 4 in the usual manner. The movable rails 2 and 2a are fastened together by a front rod 5, a head rod 6, a bridle rod 7, and a tie rod 8, and may be moved into a normal or a reverse position by means of an operating rod 9 which is connected with the head rod 6 through the medium of the usual switch basket 10. When the switch occupies its normal position in which it is shown in Fig. 1, the movable rail 2 engages the fixed rail 1, and the movable rail 2a is spaced from the fixed rail 1a. When the switch is reversed, however, the movable rail 2a then engages the fixed rail 1a, and the movable rail 2 is spaced from the fixed rail 1.

Associated with the switch A is a switch operating mechanism B embodying my invention. As here shown, this mechanism comprises a suitable casing 11 which is bolted or spiked to the ties 4 adjacent the outer side of the rail 1, and which is provided with suitable removable covers 12 whereby convenient access to the interior of the casing for inspection or repair of the mechanism may be had.

Extending downwardly through the casing 11 is a rotatable spindle or switch actuating shaft 16, and attached to the lower end of this shaft is a crank 17 which is pivotally connected with the previously described operating rod 9, the parts being so proportioned that rotation of the shaft 16 through an angle of approximately 90° will move the switch between its normal and reverse positions.

The portion of the shaft 16 which is disposed within the casing 11 is made round, and is journaled in a bearing 18 provided in the bottom of the casing 11 and in a rotatable sleeve or star block 19 which sleeve, in turn, is journaled in a bearing 20 formed in the top of the casing 11. The portion of the shaft 16 above the top of the star block bearing, however, is made square and has a somewhat smaller cross sectional area than the low portion of the shaft.

Secured to the square portion of the shaft 16 is a square sleeve 21, and slidably mounted on this sleeve is an outer sleeve 22 which is provided with a square opening to receive the inner sleeve so that both sleeves and the shaft are constrained to rotate together. When the outer sleeve 22 occupies its lowermost position on the inner sleeve, in which position it is shown in the draw-

ings, a squared portion 23 formed on the lower end of the outer sleeve enters a squared recess or socket 24 formed in the upper end of the star block 19, and under these conditions, the outer sleeve, and hence the shaft 16, is connected with the star block so that any rotation of the shaft will cause corresponding rotation of the star block. When, however, the outer sleeve 22 is moved to an upper position on the inner sleeve, the squared portion 23 on the lower end of the outer sleeve becomes disengaged from the socket 24 in the star block, and the two sleeves and the shaft are then free to rotate as a unit independently of the star block.

15 The outer sleeve 22 is arranged to be moved between its two extreme positions by means of a hand lever 27 which also serves as a means for rotating the switch actuating shaft 16 between its two extreme positions. This lever is bifurcated at one end, and the bifurcations thereof are disposed on opposite sides of a squared portion formed at the upper end of the outer sleeve, and are pivoted at their free ends on a pin 28 mounted in a lug 29 formed on the inner sleeve 21. Each bifurcation extends between a pair of lugs 30 which are secured to the associated side of the outer sleeve 22, only one pair of lugs being visible in the drawings. The parts are so proportioned that, when the lever 27 is rotated about the pin 28 to a depending position in which it is shown in the drawings, the outer sleeve 22 will be moved to its lowermost position on the inner sleeve, but that, when the lever is rotated about the pin 28 to a substantially horizontal position, the outer sleeve will then be moved to its upper position on the inner sleeve. It follows that the switch actuating shaft 16 will be connected with or disconnected from, the star block 19 according as the lever 27 occupies its depending or its horizontal position, and that, when the lever occupies its horizontal position, the shaft 16 may be rotated between its two extreme positions to move the switch points to their corresponding extreme positions by rotating the lever about the axis of the shaft, without causing rotation of the star block.

When the hand lever 27 occupies its depending position which position is its normal position, it may be locked in this position by placing a padlock 31 or other suitable locking device through a hole 32a formed in the outer end of a lug 32 which is fastened to the outer sleeve 22, and which passes through a suitable slot 33 in the lever 27. A suitable signal, here shown as a pair of vanes 34, positioned 90° with respect to each other in plan view, is fastened to the outer end of the switch actuating shaft 16, and serves to accurately indicate at all times the position of the switch.

60 The star block 19 is constantly biased to the position in which it is shown in the drawings by means of two biasing devices or spring units 35 and 36 which are disposed in the casing 11. These biasing devices are similar and a description of one will therefore suffice for both. Referring particularly to the biasing device 35 shown in Fig. 5, this biasing device comprises a cylindrical housing 37 which is provided at one end with a pair of spaced lugs 38, and at the other end with an end plate 39. Located within the housing 37 are two coil springs 40 and 41. Interposed between the left-hand end of the springs 40 and 41 and the end plate 39 is a member 42 having a centrally located hole 43. A similar member 44 provided with a centrally lo-

cated hole 45 is interposed between the other end of the springs 40 and 41 and the right-hand end of the housing 37. A rod 46 passes through the holes 43 and 45 in members 42 and 44 and also passes through a hole 47 in end plate 39. The upset end 48 of rod 46 engages the outer surface of the member 44. Threaded on rod 46 is a sleeve 49 which enters the hole 47 in the end plate 39 and bears against the outer surface of the member 42. The end plate 39 is screwed into or out of the casing 35 until the springs 40 and 41 are under the desired pressure, and the end plate is then locked in its adjusted position by bolt 50. Sleeve 51 is then screwed onto rod 46 until it engages the member 42 when the upset end 48 of the rod is tight against the member 44. Sleeve 51 is then locked in its adjusted position by means of the nut 52. With the biasing devices constructed in this manner, it will be apparent that the two springs 40 and 41 both act to bias the rod 46 to the position shown, and that movement of the rod in either direction will act to compress these springs beyond their initial compression.

The one end of the spring unit 35 is pivotally attached to the casing 11 by means of a pin 53 which passes through aligned apertures in the lugs 38, and the one end of the spring unit 36 is similarly attached to the casing 11 by means of a pin 54. The free end of the rod 46 of each of the spring units 35 and 36 is operatively connected with the star block 19 by means of a pin 55 which passes through an eye 56 screwed onto the rod, and through aligned apertures in vertically spaced lugs 57 provided on the star block. The eyes 56 are so adjusted that both biasing devices will act to bias the star block 19 to the position in which it is shown in the drawings, and the parts are so proportioned that, when the star block occupies the position shown, and the switch is connected with the star block, the switch will be yieldingly urged to whichever extreme position it then occupies. The parts are further so proportioned that, if the star block is rotated away from the position shown in a clockwise direction as viewed in Fig. 3, through an angle corresponding to the switch stroke, the force exerted on the star block by the biasing device 35 will continue to increase as the star block approaches its clockwise extreme position, but the biasing device 36 will function as a toggle, and will act to oppose the movement of the star block until the star block has been rotated approximately halfway to its clockwise extreme position, whereupon the biasing device 36 will then act to assist the further movement of the star block. The parts are still further so proportioned that, if the star block is rotated away from the position shown in a counterclockwise direction as viewed in Fig. 3, through an angle corresponding to the switch stroke, the force exerted on the star block by the biasing device 36 will continue to increase as the star block approaches its counterclockwise extreme position, but the biasing device 35 will function as a toggle and will reverse its effort after the star block has been rotated approximately halfway to its counterclockwise extreme position. The parts are further so proportioned that the total force exerted on the star block tending to restore it to its normal position will decrease as the star block is rotated away from this position, but that the force tending to return the star block to its normal position when the star block has been rotated from the position shown to either extreme position will always be 75

greater than the force tending to oppose this movement to its normal position. It follows, therefore, that when the star block has been rotated away from the position shown in either direction, as soon as the force which caused the rotation of the star block is removed, the biasing devices will act to restore the star block to the position shown.

Reciprocably mounted in the bottom of the casing 11 is a locking device 60 which, as here shown, comprises two spaced cross members 60a and 60b connected together by means of a pair of spaced stud bolts 60c and 60d. The member 60a is provided with an integral rectangular locking plunger 60g while the member 60b is provided with a centrally located hole 60k. The locking plunger 60g is slidably mounted in suitable guideways not shown and is adapted to cooperate with a lock rod L which is slidably mounted in the right-hand end of the casing 11 at right angles to the locking plunger. The lock rod L is of standard construction and comprises two longitudinally adjustable bars 63 and 64 attached at one end to the front rod 5 of the switch A and provided with two registering notches 65 so disposed that these notches will align with the locking plunger 60g when and only when the switch occupies its normal extreme position in which it is shown in the drawings.

The locking device 60 is arranged to be moved in a manner which will be described hereinafter between a right-hand extreme position in which the locking plunger enters the notches 65 in the lock rod L, and a left-hand extreme position in which the locking plunger is withdrawn from the notches 65, and it will be apparent that, when the locking device is moved to the position in which the locking plunger is within the notches 65, the switch will be positively locked in its normal extreme position, but that, when the locking device is moved to the position in which the locking plunger 60g is withdrawn from the notches 65 in the lock rod, the switch will then be unlocked.

The bolt members 60c and 60d of the locking device 60 are slidably mounted intermediate their ends in suitable lugs 66 and 67, respectively, which project upwardly from the bottom of the casing 11, and surrounding each bolt between the cross member 60a and the associated lug 66 or 67 is a partly compressed coil spring 68 which constantly biases the locking device 60 to its right-hand extreme or locking position.

A bell crank lever 69 is pivoted on a pin 70 mounted in a boss 71 formed on the side of the casing 11, and one arm 69a thereof extends downwardly and cooperates at its lower end with a lateral extension 60h provided on the cross member 60a, in a manner which will be described hereinafter. The other arm of the bell crank lever is pivotally connected at its free end with the lower end of a vertical connecting rod 74.

The connecting rod 74 extends upwardly with a sliding fit through a guideway 75 formed in the top wall of the casing 11 and is provided at its upper end with a lateral extension 74b which overlies and cooperates with an annular flange 77 formed on the sliding sleeve 22 directly above the squared portion 23. A two-piece collar 78 is bolted to the sliding sleeve 22 some distance above the annular flange 77 and the lateral extension 74b, and extending downwardly from this collar is an integral frusto conical head 79 which completely encloses the upper part of the offset portion 74b of the connecting rod 74 and

the annular flange 77, thus protecting these parts from dirt, moisture, etc.

The connecting rod 74 is also provided with another offset portion 74a which is disposed within the casing 11, and which overlies and cooperates with a cam member 80 formed integrally with the star block 19. The cam member 80 has a semicircular periphery, and its upper surface curves downwardly from each end toward the center, as shown in Fig. 2. Only one half of the cam member is visible in Fig. 2 because the other half is directly back of the half shown, but the half which is not visible is similar to the half which is visible.

The parts are so proportioned that, when the sliding sleeve 22 occupies its lowermost position, and the star block 19 occupies the position to which it is biased by the biasing devices 35 and 36, as shown in the drawings, the connecting rod 74 will move by gravity to the position in which it is shown in the drawings, which position I shall hereinafter refer to as its "lowermost" position. The parts are further so proportioned that, when the connecting rod 74 occupies its lowermost position, the underside of the lateral extension 74b of the connecting rod will engage the upper side of the annular flange 77, the offset portion 74a will engage the upper face of the cam member 80 at the lowest point of the cam face, and the bell crank lever 69 will be rotated to a position in which the arm 69a is just clear of the offset portion 60h of the locking device 60.

The locking device 60, in addition to being operatively connected with the sliding sleeve 22 and the star block 19 in the manner just described, is also operatively connected with the tie rod 8 by means of linkage which I shall now describe.

As here shown, this linkage includes a plunger bolt 81 (see Figs. 1 and 3) which extends with some clearance through the hole 60k in the cross member 60b of the locking device 60, and the head of which bolt cooperates with the right-hand side of the cross member 60b. The threaded left-hand end of the plunger bolt 81 is adjustably connected by means of a turnbuckle 82 with one end of a link 83, the other end of which link is pivotally connected with the long arm 84a of the bell crank lever 84. The bell crank lever 84 is pivotally supported in a crank stand 85, and has its short arm 84b pivotally connected with one end of an operating rod 86. The other end of the operating rod 86 is connected with the previously described tie rod 8 by means of a standard switch basket 87.

The tie rod 8 may be located at any suitable location, but will preferably be located approximately midway between the heel and the point of the switch. The crank stand 85 is secured both to a gauge plate 89 and to a bed plate 15, which latter plate is also secured to the casing of the mechanism B. It will be apparent, therefore, that any loss of adjustment between the parts due to creepage of the ties is prevented. The linkage is so adjusted that, when the switch occupies its normal extreme position, the head of the plunger bolt 81 will engage the end member 60b when the locking plunger occupies its locking position within the notches 65 in the lock rod L.

If desired, a suitable circuit controller may be provided in the right-hand end of the casing to indicate when the locking plunger occupies its proper locking position and the switch points occupy their proper positions with respect to the stock rails. This circuit controller forms no part of my present invention, and it is not, therefore,

shown in the drawings. This circuit controller may, however, be similar to that shown and described in Letters Patent of the United States No. 1,989,128, granted to me on January 29, 1935, for Railway switch circuit controllers.

The apparatus also includes a biasing device U which in the form here shown comprises a cylinder 91 containing a reciprocable piston 92 attached to one end of a piston rod 93. The cylinder 91 is pivotally connected with the one arm 94a of a link 94 which is pivotally mounted intermediate its ends on an upstanding pin 95 secured to the base of the casing 11, while the piston rod 93 is pivotally connected at its free end with the star block 19 by means of the pin 55. The arm 94b of the crank 94 is pivotally connected with one end of a link 96 the other end of which is pivotally connected with the long arm 97a of a bell crank lever 97. The bell crank lever 97 is pivotally supported on an upstanding pin 98 secured to the base of the casing 11, and the short arm 97b thereof carries a roller 99 which cooperates with a cam 100 provided on the star block. The parts are so proportioned that, when the star block occupies the position to which it is biased by the biasing devices 35 and 36, the piston 92 will occupy a projected position in which it is shown in the drawings, but that, when the star block is rotated away from the extreme position shown in either direction through a distance corresponding to the switch stroke, the rotation of the star block will act through the pin 55 and through the crank 97, link 96, and crank 94 to move the piston and cylinder relative to each other in such manner that the piston will be moved to its retracted position in the cylinder during approximately three-quarters of the stroke of the star block and will then be moved partway toward its projected position during the balance of the stroke.

Mounted in the left-hand end of the cylinder 91 of the biasing device U is a magnet valve V of the usual and well-known construction. The valve V controls communication between the cylinder 91 and the atmosphere in such manner that, when the valve is deenergized, the cylinder will be connected with atmosphere, but that, when the valve V is energized, the cylinder will be disconnected from atmosphere. The winding of the valve V is connected with the rails 1 and 1a in series with a battery B by means of a pair of wires 101 and 102 whereby this winding will become energized whenever a train moves over the switch A.

The operation of the apparatus as a whole is as follows: As shown in the drawings, the movable rails of the switch are in their normal extreme positions, and the hand lever 27 is locked in its depending position by means of the padlock 31. Under these conditions, the sliding sleeve 22 is held in its lowermost position on the inner sleeve 21, and the star block 19 is accordingly connected with the switch actuating shaft 16 so that the biasing devices 35 and 36 are effective to hold the movable rails of the switch in their normal positions. Furthermore, under these conditions, the magnet valve V is deenergized, the piston 92 of biasing device U occupies its projected position in the cylinder 91, the connecting rod 74 is held by gravity in its lowermost position, and the locking device 60 is held in its locking position by the biasing springs 68. As was previously pointed out, when the locking device 60 occupies its locking position, the movable rails of the switch are locked in their normal positions, thus

rendering the switch safe for high speed traffic over the switch in a facing point direction.

I shall now assume that it is desired to reverse the switch A. To do this, the padlock 31 is first removed from the hole 32a in the lug 32 to unlock the hand lever 27, and the hand lever 27 is then raised to its horizontal position. This preliminary movement of the hand lever raises the sliding sleeve 22 from its lowermost position in which it is shown in the drawings to its uppermost position, and as was previously pointed out, when the sliding sleeve is moved to its uppermost position, the squared portion 23 on the lower end of this sleeve becomes disengaged from the socket 24 in the upper end of the star block 19, thus disconnecting the star block, and hence the biasing devices 35 and 36 and the biasing device U from the switch actuating shaft, so that the switch actuating shaft is then free to rotate without any opposition from the biasing devices. Furthermore, when the sliding sleeve 22 is moved to its upper position, the annular flange 71 on the lower end of this sleeve cooperates with the lateral extension 74b on the connecting rod 74, to move the connecting rod 74 to its uppermost position, and this movement of the connecting rod, in turn, acts through the bell crank lever 69 to move the locking device 60 from its normal locking position in which it is shown in the drawings to a position in which the locking plunger 60g is completely withdrawn from the notches 65 in the lock rod L, thus unlocking the switch. The biasing devices and the fluid pressure motor now being disconnected from the switch actuating shaft, and the switch being unlocked, the hand lever 27 is next rotated in a horizontal plane which it then occupies, through an angle of approximately 90° in a counterclockwise direction. This intermediate movement of the hand lever rotates the switch actuating shaft 16 to the extreme position opposite to that in which it is shown in the drawings, thereby reversing the movable rails of the switch in the manner previously described. As the movable rails move to their reverse positions, the linkage which connects the locking device 60 with the tie rod 8 is actuated in such manner that the plunger bolt 81 is moved toward the left, and as soon as the plunger bolt has moved as far as the locking device 60 was previously moved by the bell crank lever 69, the head of the plunger bolt engages the end member 60b of the locking device 60, and during the balance of the movement of the plunger bolt, the locking device will be moved with the plunger bolt, so that, when the switch reaches its full reverse position, the locking device will be moved to its extreme left-hand position. The switch points now being fully reversed, the hand lever 27 is next restored to its depending position. This final movement of the hand lever, of course, restores the sliding sleeve 22 to its lowermost position, thus reconnecting the star block 19 with the switch actuating shaft 16, and at the same time permitting the connecting rod 74 to return by gravity to its lowermost position. After the hand lever has been restored to its depending position it may, if desired, be relocked in this position by again inserting the padlock 31 in the hole 32a of the lug 32.

If, when the switch has been moved to its reverse position in the manner just described, it is desired to restore the switch to its normal position, the hand lever 27 is first raised to its horizontal position, and is then rotated in a clockwise direction through an angle of 90°, as

viewed in Fig. 1, and is finally restored to its depending position and relocked in this position. The operation of the various parts of the apparatus under these conditions is just the reverse of that described above and will be readily understood from the foregoing description and from an inspection of the drawings without further detailed description.

I shall now assume that the parts are in their normal positions in which they are shown in the drawings, and that a train trails the switch. Under these conditions, as the leading wheels of the train roll along the fixed rail 1 and the movable rail 2a, the movable rails 2 and 2a will be forced over laterally, but before a sufficient force is developed at the points of these rails to overcome the opposing force of the biasing devices 35 and 36 and cause the point of the movable rail 2 to tend to move out of engagement with the fixed rail 1, the movable rails, being somewhat resilient, become bent, so that with the usual standard split switch, the tie rod 8 will be moved upwardly, as viewed in Fig. 1, three-quarters of an inch or more. This movement of the tie rod 8 acting through the switch basket 87, operating rod 86, bell crank lever 84, link 83, and plunger bolt 81 moves the locking device 60, in opposition to the bias of the springs 68, a sufficient amount to completely withdraw the locking plunger 68g from engagement with the notches 65 in the lock rod L, thus unlocking the switch. As a result, when the leading wheels of the train have reached the position in which a sufficient force is developed at the points of the movable rails to cause the point of the movable rail 2 to move out of engagement with the fixed rail 1, the movable rails will be unlocked, and these rails will therefore be forced away from their normal positions by the wheels of the train in exactly the same manner as they would be if no point lock were provided. The movement of the movable rails away from their normal positions acts through the operating rod 9 and crank 17 to rotate the shaft 16 in a counterclockwise direction, as viewed in Fig. 3, and this rotation of the shaft 16, in turn, rotates the associated sleeves 21 and 22 and hence the star block 19 in the same direction. The rotation of the star block 19 actuates the biasing devices 35 and 36 in the manner previously described so that these biasing devices now tend to constantly return the movable rails to their normal positions with a force which decreases with the displacement of the movable rails, as will be apparent from an examination of the curve 105 shown in Fig. 4. The rotation of the star block 19 also moves the cylinder 91 and piston 92 of the biasing device U relative to each other in the manner previously described, and since valve V is now energized, fluid will become compressed in the cylinder 91 during approximately 80 per cent of the stroke of the switch and will then expand during the balance of the stroke, thus causing a force to be exerted on the star block 19 which tends to complete the movement of the switch points to their full reverse positions. The force which is exerted on the switch points due to the cam reaction is illustrated graphically by the curve 106 in Fig. 4, while the force which is exerted on the switch due to the compressed fluid in the biasing device is illustrated by the curve 107, and the resultant force which is exerted on the switch is illustrated by the curve 108. It will be apparent from an examination of these curves that, when the switch points are within a

short distance of their reverse positions, the force which is exerted on the switch points by the biasing device tending to move them to their reverse positions exceeds that which is exerted on the switch points by the two spring units, and it follows that the biasing device U will therefore become effective to force the switch points to and hold them in their full reverse positions. After the train has completely passed the switch, it will move off of the track circuit in which the magnet valve V is included and will thus cause this magnet valve to become deenergized. When this happens, the fluid which was previously trapped in the cylinder 91 will become exhausted to atmosphere, and will thus remove the force which was previously exerted on the points by the biasing device U, whereupon the spring units 35 and 36 will then become effective to return the switch points to their normal positions. As soon as the points have moved toward their normal positions approximately half of their stroke, spring unit 35 will then exert a force on the points which aids that exerted on the points by the spring unit 36 and it will be apparent, therefore, that the remainder of the movement of the points to their normal positions will be relatively rapid. When the switch points have been restored to their full normal positions, all parts will then be restored to their normal positions in which they are shown in the drawings.

It should be pointed out that, with the apparatus constructed in the manner just described due to the fact that the force which is exerted on the switch points by the two spring units 35 and 36 gradually decreases as the points are moved away from their normal positions to their reverse positions by a trailing train, the force which must be exerted on the points to compress the fluid in the cylinder 91 when a train is trailing the switch will not be materially greater than that which must be exerted on the points of spring switches of the usual and well-known type.

The means for unlocking the switch as shown in Fig. 1 is arranged so that it will only function when the switch occupies its normal position and a train trails the switch. However, this means may be arranged in the manner shown in Letters Patent of the United States No. 1,992,551, granted to W. L. Stout, on February 26, 1935, for Railway switch operating apparatus, and when the means for unlocking the switch is arranged in this manner if the switch is then moved to its reverse position by the switch operating mechanism and a train trails the switch, the apparatus will then function in a manner which is similar to that just described, and which will be apparent from the foregoing description without further detailed description.

It should also be pointed out that, with the apparatus constructed in the manner described, the biasing device U takes the place of the usual buffering device so that the total equipment requirement is no greater than that employed in spring switches of the type now in use.

It should further be pointed out that, with the apparatus constructed in the manner described, since the switch points are forced to their full reverse positions while a train is trailing the switch, the wear on the points is materially reduced.

Referring now to the modified form of apparatus illustrated in Fig. 6, as here shown, the spring units 35 and 36 and the biasing device U shown in Figs. 2 and 3 have been replaced by two biasing devices U1 and U2 which also em-

body my invention. These biasing devices are similar, and a clear understanding of both will therefore be had from a description of only one. Referring particularly to the device U_1 shown in section in Fig. 7, this device comprises two air cylinders 110 and 111 secured to the opposite ends of a cylindrical spring housing 112 . A piston rod 113 extends into the cylinders 110 , the housing 112 , and the cylinder 111 through a stuffing box 114 provided in a cylinder head 115 which closes the outer end of the cylinder 110 , and secured to this piston rod within the cylinder 110 is a reciprocable piston 116 . A reciprocable piston 117 is also mounted in the cylinder 111 , and this piston cooperates at its right-hand side with an upset end 118 formed on the piston rod 113 , in a manner which will be explained more fully hereinafter. The piston 117 is guided by a suitable guide rod 119 secured to the left-hand end wall of the cylinder. Surrounding the piston rod 113 within the housing 112 are three compressed coil springs 120 , 121 , and 122 . One end of these springs abuts against a member 123 which is slidably mounted in the housing 112 , and the other end of these springs abuts against a similar member 124 which is likewise slidably mounted in the housing 112 . The two members 123 and 124 are each provided with a centrally located hole 125 which receives the piston rod 113 with some clearance, and cooperate respectively with the piston 116 and with the upset end 118 of the piston rod 113 . The members 123 and 124 also cooperate with annular shoulders 126 and 127 formed at the junction of the cylinder 110 and the housing 112 , and the junction of the cylinder 111 and the housing 112 , respectively, the parts being so proportioned that, when the members are engaging the shoulders 126 and 127 , the member 123 will just clear the piston 116 , and the member 124 will be just clear of the upset end 118 of the piston rod. It will be apparent, therefore, that the springs 120 , 121 , and 122 all act to bias the piston rod 113 to the position shown, and that movement of the piston rod in either direction from this position will act to compress these springs beyond their initial compression. The parts are further so proportioned that, when the piston rod occupies the position shown, the piston 117 will be free to move to either end of its stroke, and the piston 116 will be located in such a position that the piston rod 113 can be moved into the device U far enough to cause the upset end 118 of the piston rod to engage the piston 117 and force it from its right-hand or projected position to its left-hand or retracted position.

The cylinder 111 is provided with a port 127 through which fluid may be at times admitted to the cylinder to move the piston to its projected position, and mounted on this cylinder is a magnet valve V which connects the cylinder with, or disconnects it from atmosphere according as the valve V is deenergized or energized.

The biasing device U_1 also comprises two valves V_1 and V_2 which are mounted in the cylinder head 115 , and which are actuated by engagement with the piston 116 . The valve V_1 is of the piston type and comprises a piston 130 secured to a stem 131 , and biased to the left-hand end of a cylinder 132 in which the piston 130 reciprocates. When the piston occupies the position shown, the cylinder 110 is connected with a pipe 133 which is screwed into the outer end of the valve through a plurality of radially disposed ports 134 formed in the side wall of the

cylinder 132 , but when the piston 130 is moved toward the right, it moves past the ports 134 and disconnects the cylinder 110 from the pipe 133 .

The valve V_2 is of the poppet type and comprises a valve member 135 secured to a fluted valve stem 136 , and biased by means of a spring 137 to a position in which the member 135 engages a valve seat 138 . When the member 135 is unseated, the cylinder 110 is connected with atmosphere through a port 139 , but, when the valve is seated, the cylinder 110 is then disconnected from atmosphere. The spring 137 is made stiff enough so that any air pressure which is developed in cylinder 110 will not open the valve. The valve stem 136 is made somewhat shorter than the valve stem 131 so that, when the piston 116 is moved to its right-hand extreme position, it will engage the stem 131 and close the valve V_1 before it opens the valve V_2 .

The devices U_1 and U_2 are pivotally attached, at the ends opposite to the piston rods, to the casing 144 by means of pins 140 , and the piston rods of these devices are both pivotally attached to the star block 19 by means of the pin 55 . The pipe 133 of the device U_1 is connected to the cylinder 111 of the device U_2 at the associated port 127 , and the pipe 133 of the device U_2 is connected with the cylinder 111 of the device U_1 at the associated port 127 .

The windings of the magnet valves V are connected in parallel and are connected with the wires 101 and 102 so that the valves V will become energized whenever a train trails the switch.

The remainder of the apparatus shown in Fig. 6 is similar to that shown in Fig. 1 and will be understood from the foregoing description of Fig. 1 without further detailed description.

The operation of the apparatus shown in Fig. 6 when the switch is moved between its two extreme positions by means of the hand lever 27 is identical with that previously described in connection with Fig. 1, and this operation will therefore be understood from the foregoing description without further detailed description.

When the switch occupies its normal position and a train trails the switch, the operation of the apparatus will be similar to that shown in Fig. 1 when the switch occupies its normal position and a train trails the switch with the following exceptions. Under these conditions, the counterclockwise rotation of the star block which takes place after the switch points become unlocked in response to the movement of the points away from their normal positions by the trailing train will cause the piston rod 113 of the device U_2 to move out of the device, and will cause the piston rod 113 of the device U_1 to first move into the device until after the switch has moved to its mid stroke position whereupon this latter piston rod will again then start out of the device U_1 . The movement of the piston rod 113 of the device U_2 out of this device will cause the load exerted on the switch by the spring assembly of this device to increase while the movement of the piston rod 113 of the device U_1 will cause the spring assembly of the device U_1 to first exert a force on the switch which opposes its movement and to then exert a force on the switch which aids its movement, thus causing the total force which is exerted on the switch by the two spring assemblies to decrease as the switch points move away from their normal positions. The movement of the piston rod 113 of the device U_2 will

also cause the piston 116 of this device to move with the piston rod and, since valve V1 is then open and valve V2 is closed, the movement of the piston will compress fluid in the cylinder 110 and force it through the pipe 133 into the cylinder 111 of the device U1. When the fluid is forced into the cylinder 111 under these conditions, the magnet valve V will be energized due to the presence of the train on the switch, and the fluid which is forced into the cylinder 111 will therefore build up a pressure behind the piston 117 and will thus cause the piston 117 to move into engagement with the piston rod 113 and exert a force on this piston rod which aids that due to the spring assembly in urging the switch points to their full trailed positions. Fluid will continue to be compressed in the cylinder 110 of the device U2 and to be forced into the cylinder 111 of the device U1 until the switch points have been moved approximately 80 per cent of their stroke at which time the piston 116 of the device U2 will close valve V1 of this device and open the valve V2. This retains the pressure in the cylinder 111 of the device U1 and releases it from the cylinder 110 of the device U2. The forces exerted on the switch points by the various parts of the devices U1 and U2 during the movement of the points is illustrated graphically in Fig. 8, and it will be apparent from an inspection of this figure that, when the switch points have moved approximately four-fifths of their stroke, the combined force due to the fluid in the cylinder 111 of the device U1 and the spring assembly of this device will exceed the opposing force due to the spring assembly of the device U2 with the result that the switch points will be forced to their full trailed positions by the device U1. The valve V will remain energized until after the train has completely passed the switch, and it follows, therefore, that the switch points will be held in their full reverse positions until the train has completely passed the switch and deenergized the valve V. When this happens, the fluid which was previously trapped in the cylinder 111 of the device U1 will be allowed to escape to atmosphere, whereupon the force which is exerted on the switch points by the device U1 will become less than that exerted on the switch points by the device U2, and the device U2 will therefore start to return the switch points to their normal positions. As soon as the switch points have been returned approximately halfway toward their normal positions, the device U1 will then become effective to assist the device U2 in completing the movement of the switch points and it follows, therefore, that the points will return rapidly to their normal positions. As soon as the switch points have been returned to their normal positions, all parts will then be returned to the positions in which they are shown in the drawings.

If the switch is moved to its reverse position by means of the hand lever and a train trails the switch, the switch will, of course, be unlocked so that the locking mechanism will not function, but the devices U1 and U2 will be effective to force the switch points to their full normal positions and retain them there until after the train has passed the switch in a manner which will be readily understood from the foregoing description it being noted that, under these conditions, the device U2 will function as a toggle instead of the device U1. It should also be noted that, under these conditions, when the switch points have been moved to their normal positions, the locking plunger will be prevented from entering

the notches in the lock rod and locking the switch in their normal position by the cooperation between the cam 80 and the cam follower 14.

It should be particularly pointed out that, while the air is retained in the air cylinders in the two forms of apparatus previously described, the mechanism would function in practically the same manner if a small orifice were provided in place of the pin valves. Under these latter conditions, the switch would remain in its full trailed position until the compressed fluid had leaked out through the restricted orifice to the point where the pressure which was exerted on the switch points by the active air cylinder was insufficient to overcome the opposing force tending to return the points to their normal positions. The time necessary for the compressed fluid to leak out of the cylinder could be adjusted by varying the size of the orifice and by properly varying the size of the orifice the switch could be retained in its trailed position for a period of time which would be long enough to permit a train trailing the switch at the usual speeds to completely pass the switch. If the time required for a train to trail the switch exceeded that required for the compressed fluid to leak out of the active cylinder, the mechanism would, of course, release and the switch points would then have to be forced back to their trailed position by the trailing train, whereupon the switch points would again be retained in their trailed positions for another time interval.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In combination, a railway switch of the type adapted to be trailed, a switch actuating shaft operatively connected with said switch, means connected with said shaft for operating said switch between its two extreme positions and for biasing said switch to a selected extreme position, and means including a fluid pressure device operatively connected with said shaft and supplied with fluid pressure by the movement of a train trailing said switch to apply to said switch a force which opposes and exceeds the force of said biasing means.

2. In combination, a railway switch of the type adapted to be trailed, a switch actuating shaft operatively connected with said switch, means connected with said shaft for manually operating said shaft between two extreme positions to actuate said switch between its two extreme positions and for biasing said shaft to whichever position it is operated with a force which decreases with the displacement of the switch when a train trails the switch, and a fluid pressure motor operatively connected with said shaft and supplied with fluid pressure by the movement of the switch points when a train trails said switch for applying to said switch a force which opposes and exceeds the force of said biasing means.

3. In combination, a railway switch of the type adapted to be trailed, a switch actuating shaft, means at times connected with said shaft for biasing said shaft to a selected extreme position with a force which decreases with the displacement of the switch when a train trails the switch, a fluid pressure device provided with a valve

- which becomes closed when a train trails the switch, and means connecting said device with said shaft in such manner that the resultant movement of said shaft when a train trails the switch and said valve is closed will cause fluid to become compressed in said device during a portion of the switch stroke toward its trailed position and allow it to expand during the balance of the switch stroke to apply to said switch a force which in the trailed position of the switch opposes that due to said biasing means.
4. In combination, a railway switch of the type adapted to be trailed, a switch actuating shaft, means at times connected with said shaft for biasing said shaft to a selected extreme position with a force which decreases with the displacement of the switch when a train trails the switch, a fluid pressure device provided with a valve which becomes closed when a train trails the switch, and means connecting said device with said shaft in such manner that the resultant movement of said shaft when a train trails the switch will cause fluid to become compressed in said device during a portion of the switch stroke toward its trailed position and allow it to expand during the balance of the switch stroke to apply to said switch a force which in the trailed position of the switch opposes and exceeds that due to said biasing means.
5. In combination, a railway switch of the type adapted to be trailed, a switch actuating shaft, means at times connected with said shaft for biasing said shaft to a selected extreme position with a force which decreases with the displacement of the switch when a train trails the switch, a fluid pressure device provided with a valve which becomes closed when a train trails the switch, and means connecting said device with said shaft in such manner that the resultant movement of said shaft when a train trails the switch will cause fluid to become compressed in said device during a portion of the switch stroke toward its trailed position and allow it to expand during the balance of the switch stroke to apply to said switch a force which urges the switch points to and holds them in their trailed positions until after the trailing train has passed the switch.
6. In combination, a railway switch, a switch actuating shaft operatively connected with said switch, a star block journaled on said shaft, manually operable means for rotating said shaft between two extreme positions corresponding to the extreme positions of said switch and for connecting said star block with said shaft in either extreme position to which it is rotated, means for biasing said star block to one position in such manner that the biasing force will decrease as it is rotated away from said one position, a fluid pressure motor provided in one end with a valve which becomes closed when a train trails the switch, and means for operatively connecting said motor with said star block in such manner that when said star block is connected with said shaft and a train trails the switch fluid will become compressed in said motor during a portion of the switch stroke and will expand during the remainder of the stroke to exert a force on the star block which opposes that due to said biasing devices.
7. In combination, a railway switch, a switch actuating shaft operatively connected with said switch, a star block journaled on said shaft, manually operable means for rotating said shaft between two extreme positions corresponding to

the extreme positions of said switch and for connecting said star block with said shaft in either extreme position to which it is rotated, means for biasing said star block to one position in such manner that the biasing force will decrease as it is rotated away from said one position, a fluid pressure motor provided in one end with a valve which becomes closed when a train trails the switch, and means for operatively connecting said motor with said star block in such manner that when said star block is connected with said shaft and a train trails the switch fluid will become compressed in said motor during a portion of the switch stroke and will expand during the remainder of the stroke to exert a force on the star block which opposes and exceeds that due to said biasing devices.

8. In combination, a railway switch of the type adapted to be trailed, a switch actuating shaft operatively connected with said switch, means operatively connected with said shaft for moving said switch between its two extreme positions and for biasing said switch to whichever extreme position it is moved, an air cylinder, means for connecting said cylinder with said shaft in such manner that the piston of said cylinder will move from a projected position to a retracted position and partway back to its projected position when a train trails the switch, a magnet valve connected with the end of said cylinder toward which said piston moves when it moves toward its retracted position and effective when energized for disconnecting said cylinder from atmosphere, and means for energizing said magnet valve when a train trails the switch.

9. In combination, a railway switch of the type adapted to be trailed, a switch actuating shaft operatively connected with said switch, means operatively connected with said shaft for moving said switch between its two extreme positions and for biasing said switch to whichever extreme position it is moved, an air cylinder, means for connecting said cylinder with said shaft in such manner that the piston of said cylinder will move from a projected position to a retracted position and partway back to its projected position when a train trails the switch, a magnet valve connected with the end of said cylinder toward which said piston moves when it moves toward its retracted position and effective when energized for disconnecting said cylinder from atmosphere, and means for energizing said magnet valve when a train trails the switch, the parts being so proportioned that the fluid which becomes compressed in said cylinder when a train trails the switch will force the switch points to their trailed positions and hold them there until said magnet valve becomes deenergized.

10. In combination, a railway switch of the type adapted to be trailed, a switch actuating shaft operatively connected with said switch, a rotatable star block, manually operable means for rotating said shaft between two extreme positions corresponding to the extreme positions of said switch and for connecting said star block with said shaft in either extreme position of the shaft, means connected with said star block for biasing said star block to one position in such manner that the biasing force will decrease when said star block is moved away from said one extreme position, and other means connected with said star block and effective while a train is trailing the switch for exerting on said star block a force which opposes and exceeds the force of said biasing means.

11. In combination, a railway switch of the type adapted to be trailed, a switch actuating shaft operatively connected with said switch, a rotatable star block, manually operable means for rotating said shaft between two extreme positions corresponding to the extreme positions of said switch and for connecting said star block with said shaft in either extreme position of the shaft, means connected with said star block for biasing said star block to one position in such manner that the biasing force will decrease when said star block is moved away from said one position, a fluid pressure cylinder containing a reciprocable piston attached to a piston rod, means for operatively connecting said cylinder and said piston rod with said star block in such manner that the piston of said cylinder will move from a projected position to a retracted position and partly back to its projected position when a train trails the switch, a magnet valve connected with the end of said cylinder toward which said piston moves when it moves toward its retracted position and effective when energized for disconnecting said cylinder from atmosphere, and means for energizing said magnet valve when a train trails the switch.

12. In combination, a railway switch of the type adapted to be trailed, a switch actuating shaft operatively connected with said switch, means connected with said shaft for operating said switch between its two extreme positions and for normally biasing said switch to a selected extreme position, means including a fluid pressure device operatively connected with said shaft and supplied with fluid pressure by the movement of said shaft when a train trails the switch to apply to said switch a force which opposes and exceeds the force of said biasing means.

13. In combination, a railway switch of the type adapted to be trailed, a switch actuating shaft operatively connected with said switch, means connected with said shaft for biasing said switch to one extreme position in such manner that when said switch is moved away from said one extreme position by a trailing train the biasing force will decrease, and fluid pressure means connected with said shaft and supplied with fluid pressure by a train trailing said switch from said one position for applying to said shaft a force which opposes that due to said biasing means.

14. In combination, a railway switch of the type adapted to be trailed, a switch actuating shaft operatively connected with said switch, means connected with said shaft for biasing said switch to one extreme position in such manner that when said switch is moved away from said one extreme position by a trailing train the biasing force will decrease, and fluid pressure means connected with said shaft and supplied with fluid pressure by a train trailing said switch from said one position for applying to said shaft a force which opposes that due to said biasing means, and which is sufficient to force said switch to and hold it in its other extreme position until after the trailing train has passed said switch.

15. In combination, a railway switch of the type adapted to be trailed, a switch actuating shaft operatively connected with said switch, means connected with said shaft for biasing said switch to one extreme position, and fluid pressure means connected with said shaft and supplied with fluid pressure by a train trailing said switch from said one position for applying to said shaft a force which opposes that due to said biasing means.

16. In combination, a railway switch of the type adapted to be trailed, a switch actuating shaft operatively connected with said switch, means connected with said shaft for biasing said switch to one extreme position, and fluid pressure means connected with said shaft and supplied with fluid pressure by a train trailing said switch from said one position for applying to said shaft a force which opposes that due to said biasing means and is sufficient to force said switch to and hold it in its other extreme position until after the trailing train has passed said switch.

17. In combination, a railway switch of the type adapted to be trailed, a rotatable switch actuating shaft, means operatively connecting said shaft with said switch, biasing means connected with said shaft and effective for biasing said switch to a selected extreme position, a first fluid pressure device operatively connected with said shaft and effective when said switch is trailed from its selected extreme position and said device is supplied with fluid pressure for exerting a force on said shaft which opposes and exceeds the force of said biasing means, a second fluid pressure device, means for operatively connecting said second device with said shaft in such manner that when said switch is trailed from its second extreme position fluid will become compressed in said second device, and means for supplying the fluid compressed in said second device to said first device.

18. In combination, a railway switch of the type adapted to be trailed, a casing containing a rotatable switch actuating shaft, means operatively connecting said shaft with said switch, biasing means connected with said shaft and effective for biasing said switch to a selected extreme position, two fluid pressure devices operatively connected with said shaft and with each other in such manner that when a train trails said switch from said selected extreme position fluid will become compressed in the one device and will be supplied to the other device to cause a force to be exerted on said shaft which opposes and exceeds the force of said biasing means, and means effective after a train has trailed said switch for venting the fluid supplied to said other device to atmosphere.

19. In combination, a railway switch of the type adapted to be trailed, a casing containing a rotatable switch actuating shaft, means operatively connecting said shaft with said switch, a star block journaled in said casing, manually operable means for rotating said shaft between two extreme positions corresponding to the two extreme positions of a railway switch and for connecting said star block with said shaft in either extreme position of said shaft, two biasing devices each including two air cylinders secured to the opposite ends of a cylindrical housing, a piston rod extending into the two cylinders and the housing of each device, a piston secured to each piston rod within one of the associated cylinders, a piston reciprocably mounted in each of the other cylinders of each device and cooperating with the inner end of the associated piston rod, a normally closed and a normally open valve in the end of said one cylinder of each device toward which the associated piston moves when the piston rod is moved out of the cylinder operated by the piston when the piston is moved to one end of its stroke in such manner that the normally open valve will close before the normally closed valve opens and effective respectively for controlling communication be-

- tween the associated cylinder and atmosphere and the associated cylinder and said other cylinder of the other biasing device on the side opposite the piston rod, means in the housing of
5 each device for biasing the piston rod to one position, means for pivotally connecting the piston rod of each device with said star block and the opposite end with said casing in such manner that the star block is biased by both devices to
10 one position but that when the star block is rotated away from said one position through an angle corresponding to the switch stroke in one direction the piston rod of the one device will be moved out of the device and the other piston rod
15 of the other device will first be moved into the device and then out and that when the star block

is rotated away from said one position through an angle corresponding to the switch stroke in the opposite direction the piston rod of the other device will be moved out of the device and the piston rod of the one device will first be moved into the device and then out, whereby when a train trails the switch the biasing force exerted on the switch due to the biasing means of each device will decrease, a magnet valve connected with said other cylinder of each device on the side opposite the piston and effective when energized for disconnecting the associated cylinder from atmosphere, and means for energizing said valves whenever a train trails the switch. 5 10 15

HERBERT L. BONE.
